UNITED STATES PATENT OFFICE.

NELSON KROHN, OF CHICAGO, ILLINOIS, ASSIGNOR TO THE ADAMS & WESTLAKE COMPANY, A CORPORATION OF ILLINOIS.

SANITARY CAR-HOPPER.

1,343,730.

Specification of Letters Patent. Patented June 15, 1920.

Application filed May 26, 1916, Serial No. 99,951. Renewed June 22, 1918. Serial No. 241,436.

To all whom it may concern:

Be it known that I, NELSON KROHN, a citizen of the United States, residing at Chicago, in the county of Cook and State of Illinois, have invented certain new and useful Improvements in Sanitary Car-Hoppers, of which the following is a specification.

My invention relates to lavatory or closet hoppers and has particular reference to the forms of construction employable by railway car constructors. The object of the present invention is to simplify the construction, make more certain the operation, reduce the cost, and make installations and repairs of these hoppers and valve operating parts less complicated. Another particular object of this invention is to aid the water flush with an air flush to meet the peculiar conditions attending hoppers exposed to the air currents and air vortexes produced by a fast moving train which has made it difficult to prevent soil adhering to spaces between the usual bowl and the floor-supported hopper or base portion. I apply the water flush in the usual manner through the hollow rim of the bowl portion and the air flush about the exterior of the lower outlet end of the bowl.

The invention will be more readily understood by reference to the accompanying drawing, in which

Figure 1 is a side elevation partly in section and partly broken away of my improved hopper and bowl and the air and water flushing mechanisms connected therewith.

Fig. 2 is a section taken on line X—X; Fig. 3, a section taken on line Y—Y, and Fig. 4, a section taken on line Z—Z of Fig. 1, on a reduced scale.

In the several views the improvement in the hopper body construction resides in casting the bowl-portion 2 and floor stand portion 3 in one piece with a contracted outlet portion in the form of a flange 4 which is a continuation of the bowl portion 2 projecting into the portion 3 provided with a flange 5 resting on the floor 6 in the usual way. The upper edge of the bowl 2 is inwardly rolled to provide the usual water channel or trough 8 into which the flushing water is introduced tangentially from the source of supply (not shown) and under more or less pressure. The usual open seat 9 and cover 10 therefor are both pivoted as 56 at 11 to a lug 12 on the body of the hopper

or its upper bowl portion 2. The pipe leading from a source of water supply to the valve mechanism for the flushing operation is indicated by the numeral 13 as a broken off pipe section. Said pipe is connected to a 60 valve casing 14 through the medium of a hub 15 on the casing onto which a collar 16 with an inwardly projecting flange 17 is threaded. On the pipe 13 is an outwardly projecting flange 18 between which and the flange 17 a packing ring 19 is interposed. The lower end of the valve casing has the form of a hub 20 which has threaded connection with a connecting sleeve 21 which couples the hub 20 to a pipe bend or elbow 70 22 leading into the channel 8 and which may be connected in any usual or approved manner. The valve casing 14 has a lateral bulge or enlargement 23 in which is a valve-stem-moving crank-arm 24 that is secured to a 75 short shaft 25 suitably mounted in the walls of the casing portion 23 and connected at 26 pivotally to a valve stem 27. On the same shaft 25, but exteriorly of the casing portion 23, is secured an operating lever 28, the 80 load end of which is pivoted at 29 to a connecting rod 30 pivoted at 31 to a crank 32 that is secured to the outer end of a shaft 33, which, like the shaft 25, is mounted in the walls of a valve case 34 on which is 85 an inlet hub 35 and an outlet hub 36 for an air-flushing current. Within the casing 34 and secured to the shaft 33 is a hub 37 that carries a curved valve stem 38 with a valve or ball 39 closing an opening or valve seat 40 90 and controlling the passage between the inlet hub 35 and outlet hub 36. Into the hub 35 is threaded an air nozzle 41 on which is an end flange 42 which bears against the end of the hub 35 and into which is threaded an 95 air pipe 43 which may be connected with any suitable source of air under pressure, as with the air brake air cylinders of a car. Into the outlet hub 36 is threaded one end of a nipple or short pipe section 44 with 100 which an air pipe 45 is connected for slideable adjustment. On the nipple 44 is an exterior flange 46 which may have parallel sides to adapt it for engagement with a wrench. A slip joint collar 46' with an in-turned flange 47 is threaded onto the other end of the nipple and between said flange and the end of the nipple a packing 48 is interposed to make the joint fluid tight. The lower end of the pipe 45 is connected with 110

2
a hub 49 on the hopper arranged tangentially to a space 50 between the parts 3 and 4 in which a whirling current of air is set up simultaneously with the water flush operation, as will more fully be pointed out hereinafter.

Referring, first, to the water-flush valve mechanism connected with the casing 14, 51 is a collar shrunk or otherwise secured onto 10 the valve stem 27. On this collar rests a valve or valve opening plug 52 controlling a seat or opening 53 between the inlet pipe 13 and the outlet hub 20 of the casing 14. On the valve 52 is a ring or washer 54 which 15 serves as an end thrust bearing for a short sleeve 55 mounted on the stem 27. On said stem and supported by the upper end of the sleeve is another washer 56 between which and a second like washer 57 is held 20 a dished rubber or fiber disk 58. The upper end of the stem 27 is threaded and carries a nut 59 which holds the parts mounted on the stem in assembled relation between the nut and the collar 51. Within the stem 25 27 is an axial bore 60 the ends of which lead into horizontal bores 61 and 62 communicating with the space within the casing 14. The normal volume of flow through the bores 60, 61 and 62 is modified by means of 30 a screw 63 which has threaded engagement with a threaded bore in the upper end of the stem which is substantially a threaded end portion of the bore 60. The screw 63 is arranged to have its lower end 64 projected partially across the bore 62 to restrict to the required extent the passage therethrough, which passage affords a limited opening between the water always under pressure in pipe 13 and above the valve 40 52 with the space in the casing 14 that is back of the piston composed of disks 56, 57 and 58. On the upper end of the casing 14, which is cylindrical, is a cap 65 which is threaded into the upper end of the casing 45 so that it may be conveniently removed or longitudinally adjusted to vary the pressure of a spring 66 the upper end of which bears against the cap and the lower end of which bears against the ring or washer 57. The 50 cap has a flange 65' between which and the casing 14 a suitable packing ring (not shown) may be placed, if necessary.

Depending from the air casing 34, and 55 preferably an integral part thereof, is a piston cylinder 67 in the upper end of which is a small bore 68 which places the interior of the cylinder in communication with the interior of the casing 34 and the air pipe 43. The lower end of the cylinder is closed 60 by a cap 69 which is screw-threaded onto the cylinder and is provided with a bore 70 for a piston rod 71 with a reduced and threaded upper end 71' carrying a piston head consisting of a disk or washer 72, a 65 similar and somewhat smaller disk 73, and

a leather or fiber disk 74 held between the metal disks by means of a nut 75 which has threaded engagement with the upper end 71' of the rod 71. Between the cap 69 and the cylinder 67 a packing ring 76 is interposed as a cushion contact for an annular flange 72' formed on the bottom side of the disk 72. The cap 69 has an inner flange 70' between which and the outer flange of the cap is placed a packing washer 76 which prevents frictional contact of the latter with the piston rod 71.

The usual receiving or dump pan —77— for railway car purposes is herein shown as made of two bowl-shaped sheets of metal, preferably brass, the upper and shallower one having a flange 77' which engages the lower part and is secured thereto in any suitable manner. The flange 77' is secured to a hub 78 (indicated by dotted lines) secured to a shaft 79 suitably mounted in opposite sides of the hollow base portion 3. One end of the shaft projects to the outside of the part 3 and has on its projecting portion a hub 80 carrying a crank arm with a slot 81 in its free end that is engaged by a wrist-pin 82 on the piston rod 71.

There being water under pressure in the casing 14 and air under pressure in the casings 34 and 67, when the lever 28 is swung down the valve 52 will be opened to admit water into the bowl and simultaneously by reason of the connecting rod 30 the air valve 39 will swing away from its seat on the pivot 33 causing a rush of air through the pipe 45 into the annular space 50 and around the pan to counteract the upward draft from below the floor which has caused much annoyance to railway operators on account of the problem of eliminating odors in the car emanating from the lavatory and to sweep away from the wall of the base any filth which might be thrown against it. The air suction created in the casing 34 will force up the piston on the stem or rod 71 and by rotating the axis of the pan 77 it will be tilted and dumped. Instantaneous return of the lever when released by the operator is prevented, and the water and air valves held open the required duration of time, by reason of the water above the piston 56, 57 and 58 having been forced out partly through the by-pass 62, 60 and 61 in opening the valve 52. The closing movement of the valve occurs only as the upper chamber in the casing 14 is refilled through the restricted passage. The speed of return to closed position of the air and water valves is regulated by means of the screw 63 controlling the volume or rate of flow of water 120 that is returned to the cylinder 14 above its piston after the lever 28 has been released by the manipulator of it. The closing of the air valve 39 will change the suction upward through the opening 68 into a 125 130

downward air pressure upon the piston on the stem 71 and swing the pan back to normal position on its axis 80. So far as operation of the pan 77 is concerned the effect 5 would be substantially the same if the rods 71 and 27 are joined either by pivoting them together or in that event suitably alining the parts. Hence my improvements have provided a water valve construction that is 10 adapted to operate the pan.

By mounting my restraining piston on the valve or on my upward extension of the valve stem, I obviate the common difficulty experienced with separate piston 15 chambers and pistons having a lever or other connection with the valve stem, namely, the drying out of the fibrous or leather portion of the piston head, which in the present instance includes, substantially, 20 the disks 56, 57 and 58 and their retaining nut 59. Looseness of the friction portion of the piston also causes a shortening of the life of the valve 52, which then will be seated violently or hammer its seat.

25 During the opening movement of the valve 52 part of the water may escape past the edges of the leather of fiber disk 57 from the buffer space above the piston, but as the return movement tends to press the 30 edges of the disk against the sides of the cylinder the return movement will be restricted to the extent that the vacuum above the piston is relieved through the by-pass 60, 61 and 62. This replacement of vacuum 35 is, of course, always uniform and subject to positive control through the medium of the screw 63. If the return to the valve seat of the valve 52 is too rapid, and the prolongation of flushing accordingly insufficient, projecting the inner end or point 64 of the screw farther into the by-pass will retard the seating of the valve and prolong 40 the flow of the flushing stream.

While an operative and preferred form of 45 construction is disclosed, various changes of detail may be made without departing from its scope. I do not limit myself to the employment of air as the means for flushing the base, as any suitable fluid may be used.

50 Having thus described my invention, I claim as new and desire to secure by Letters Patent.

1. The combination with a closet hopper having a bowl portion and a base portion, of 55 means for water-flushing said bowl portion, and means for air flushing said base portion beneath said bowl portion.

2. The combination with a closet hopper having an upper bowl portion and a lower 60 base portion, of a tilting pan under said bowl portion, means for water flushing said bowl portion, and means for air flushing and air-actuating said pan.

3. The combination with a closet hopper

having a channeled bowl for water flushing, 65 and a channeled base for air flushing, of a pan in said base, and means operable by a single lever for water flushing said bowl, air flushing said base around the pan and for tilting said pan. 70

4. The combination with a closet hopper comprising a bowl and a base, of a pivoted pan underneath said bowl, and means for pneumatically actuating said pan and at the same time creating a current of air around 75 said pan.

5. The combination with a closet hopper comprising a bowl and base therefor, of a pivoted dumping pan, a piston-operated device for dumping said pan and restoring it 80 to normal position under said bowl, an air conduit leading to the exterior of said pan, and a single valve controlling the flow of air through said air conduit and the movement of the piston-operated device. 85

6. The combination with a closet hopper, of a valve controlled water conduit leading to the upper portion of said hopper, an air-controlled dumping pan, pneumatic means for operating same, an air conduit leading 90 to the exterior of said pan, an air valve controlling the flow through the latter conduit, and means causing said air valve to control said pneumatic means.

7. The combination with a closet hopper 95 having a pivoted dump pan underneath the bowl portion of said hopper, and with the valve-controlled flushing conduit for said hopper and bowl, of a flush-operating lever, a piston cylinder, a piston-rod or stem movable by said lever, a piston on said rod or stem movable in said cylinder, a valve on said rod or stem controlling said flushing conduit, means for retarding the movements of said valve and piston, and means operating in conjunction with the movements of said valve and piston, for operating said dump pan. 100

8. In a closet hopper, in combination, a bowl portion, a base portion, means for 110 water flushing said bowl portion, means for introducing a jet of air tangentially into said base portion.

9. The combination, in a hopper closet, of a bowl section and a base section, the bottom of the bowl having the form of an annular flange depending into and being of less diameter than the base section, and means for introducing a jet of air tangentially into the space inclosed between such 115 flange and the wall of the base. 120

10. In a closet hopper, in combination, a base portion, a bowl portion whose outer wall forms a continuation upward of said base portion and having a downwardly extending annular lip projecting into the base portion forming an annular recess in the upper portion of the base portion, means 125

for flushing said bowl portion, and means for introducing a jet of flushing fluid tangentially into said annular recess.

11. In a closet hopper, in combination a base portion, a bowl portion whose outer wall forms a continuation upward of said base portion and having a downwardly extending annular lip projecting into the base

portion forming an annular recess in the upper portion of the base portion, means for flushing said bowl portion, and means for introducing a jet of air tangentially into said annular recess. 10

In testimony whereof I have hereunto signed my name.

NELSON KROHN.
